CAN ATTACHMENT

George D. Brougham, Gillett, Pa.

Application October 6, 1938, Serial No. 233,622

1 Claim. (CL 91—63)

The invention relates to a can attachment and more especially to a wiper attachment for paint cans.

The primary object of the invention is the provision of an attachment of this character, wherein the same when applied to a can serves as a wiper for the brush to remove surplus paint and also will act to hold the brush when not in use, the attachment being readily and easily applied to the body of the can and will not interfere with free access to the contents thereof when its lid or cover is removed.

Another object of the invention is the provision of an attachment of this character, wherein the same is of novel construction and is made from several pieces of inherently resilient wire having the required resiliency and strength to enable the easy mounting thereof on the can body and functioning as a wiper and holder for a brush.

A further object of the invention is the provision of an attachment of this character, which is extremely simple in its construction, thoroughly reliable and efficient in operation, readily and easily applied to and removed from a can body, and inexpensive to manufacture and install.

With these and other objects in view, the invention consists in the features of construction, combination and arrangement of parts as will be hereinafter more fully described, illustrated in the accompanying drawing, which discloses the preferred and modified forms of embodiment of the invention and pointed out in the claim hereunto appended.

In the accompanying drawing:

Figure 1 is a fragmentary side elevation of a paint can showing the attachment in its preferred form, constructed in accordance with the invention and applied thereto.

Figure 2 is a top plan view showing by dotted lines one adjusted position and by full lines another adjusted position.

Figure 3 is a view similar to Figure 1 showing a modification.

Figure 4 is a top plan view of the form shown in Figure 3.

Similar reference characters indicate corresponding parts throughout the several views in the drawing.

Referring to the drawing in detail, particularly Figures 1 and 2, A designates generally a portion of a paint can, being of conventional form, and has, as usual, the removable cover (not

shown), the can body being open at its top for accommodation of a paint brush, a portion thereof being indicated at B while at C is the attachment constituting the present invention and hereinafter fully described.

The attachment C comprises a single length of wire 10 having inherent resiliency and strength, being bent simulating a partial hoop or ring of a size to frictionally engage exteriorly about the body of the can A next to the top flange 11 for separable fastening to the said body of the can in contacting relation to the flange. The ends of the wire 10 are upturned and formed into eyes 12 with which is loosely connected a swinging bail 13 which bridges the open top of the can A and this bail constitutes a wiper for the brush B when in use. The bail 13 is swingable to be disposed crosswise of the open top of the can A or to one side thereof, as shown by dotted lines in Figures 1 and 2 of the drawing, while in full lines the bail 13 is in position for wiping service.

The wire 10 is clipped exteriorly for partially embracing the body of the can A and is so worn in that manner upon the can.

In Figures 3 and 4 of the drawing there is shown a modification wherein the wire 14, which is bent corresponding to the wire 10, has the downturned terminal eyes 15, these having loosely connected thereto the swingable bail 16, which is similar to the bail 13, and constitutes a wiper and a brush holder or rest.

What is claimed is:

An attachment for a cylindrical can having an open end and an external annular bead exteriorly of said can at the open end, comprising an inherently resilient single curled wire having a length and shape to partially encircle the external diameter of said can for a distance slightly greater than one-half of its diameter for separable frictional fastening thereto next to the bead, terminal eyes formed at opposite ends of said wire and bent upwardly at right angles to its plane, and an inverted substantially U-shaped bail having short side arms loosely connected with said eyes for vertical swinging movement and for bridging the open end of said can within the diameter thereof when at rest upon the said bead and effecting a wiper for a brush and a rest therefor and also a handle for the carrying of said can when in another position.

GEORGE D. BROUGHAM.
